PACKAGE COVERING

Earl L. Aiken, Hickory, N. C.

Application May 13, 1955, Serial No. 508,233

1 Claim. (Cl. 229—51)

This invention relates to enclosures or coverings and more particularly to a covering or an enclosure provided as the original protective wrapping for a package of cigarettes, cereal, crackers and the like and which covering or enclosure may be used to enclose the top of the package after the same has been opened.

Much difficulty has been encountered in keeping the contents of packages free from moisture after the same has been opened. It is therefore an object of this invention to provide a flexible inexpensive covering as the original protective wrapping of a package which covering is provided with suitable reinforcement so the same can be removed from the package when the same is opened and inverted to be placed over the open end of the package.

Another object of the invention is to provide reinforced sides and a reinforced end for a flexible covering or enclosure whereby when a package is enclosed or covered with the same and later opened, the reinforced end of the covering will act as a top wall for enclosing the open end of the package and the reinforced sides of the covering or enclosure will aid in guiding the covering or the enclosure along the sides of the package to close the open end of the package and to reinforce the sides of the package.

A further object of the invention is to provide a novel method of covering a package.

Some of the objects of the invention having been stated, other objects will appear as the description proceeds when taken in connection with the accompanying drawings, in which—

Figure 1 is an isometric view with the covering or enclosure applied to a package of cigarettes;

Figure 2 is an isometric view of the covering applied to a package of cigarettes after the same has been opened;

Figure 3 is an isometric view of the covering applied to a package of cigarettes wherein the covering is shown placed in inverted position to enclose the open end of the package of cigarettes;

Figure 4 is a vertical section taken substantially along line 4—4 of Figure 3 and showing the covering or enclosure in normal position as applied to an open package of cigarettes to enclose the open end thereof;

Figure 5 is a reduced isometric view of the stiffening means removed from the enclosure.

Referring more specifically to the drawings, it will be observed that the reference numeral 10 broadly indicates an air-tight and moistureproof foldable covering or enclosure having a body portion 11 and end walls 12 and 12' enclosing a package P. A pull tab or tear tape 13 is provided for separating the end wall 12' from the body portion 11 of the enclosure 10 when the package P is to be opened.

The enclosure 10 is shown in the drawings as applied to a package of cigarettes and in this instance is preferably formed from a transparent material such as cellophane. However, the material for the enclosure 10 may vary with the type of package being enclosed and may comprise

2

waxed paper, aluminum foil or other similar wrapping media as desired.

In many instances it is desired to preserve a portion of the contents of a package after the end wall 12' has been removed from the body portion 11 by manipulation of the tear tape 13, and the present invention provides a novel means and method whereby the remaining contents of an opened package may be substantially protected from air and moisture. It has been found that the remaining contents of an opened package may be preserved by first removing the remainder of the enclosure 10 and then repositioning the same in hood-like fashion over the open end of the package.

In order to facilitate the repositioning of the remainder 15 of the enclosure 10, there are provided opposed side reinforcement or stiffening members 14 and 15 adjacent at least two opposite surfaces of the body portion 11, and in some instances it may be desirable to connect corresponding ends of the stiffening members 14, 15 by an 20 additional reinforcement or stiffening member 16 disposed adjacent the end wall 12 to thus form a U-shaped reinforcement member. The reinforcement members 14, 15, 16 are preferably formed from thin relatively stiff cardboard but any other relatively stiff material may be employed, and any desired reinforcing means such as indicated at 14, 15 and 16 in the drawings may be either 25 formed integral with the body portion 11 and end wall 12 or secured thereto by suitable means such as adhesive or heat-sealing.

30 Although the drawings disclose the reinforcements 14, 15 as being secured to the inner surface of the side walls of the body portion 11 it is to be understood that such reinforcements may, if desired, be secured instead to the outer surface of the side walls or to either surface of the 35 front and rear walls of the body portion 11. In a like manner the reinforcement 16 may be secured to either the inner or outer surface of the end wall 12, or may be omitted entirely if desired.

It is also contemplated that the reinforcements 14, 15 40 and 16 may form a skeleton framework for the enclosure whereby the flexible material, such as cellophane, which comprises the remainder of the enclosure may be connected in overlapping relation to portions of the reinforcements, rather than extend completely thereabout as 45 shown in the drawings.

It will be observed in Figure 1 that the top edge portions of the reinforcement members 14 and 15 are disposed just beneath the pull tape 13 so that the said top edges form the leading edges of the hood-like enclosure 50 when the same is repositioned about the package P. In order to re-enclose a package P after the end wall 12' has been removed from the body portion 11 by manipulating the tape 13 to remove the end wall 12', the remainder of the enclosure 10 is removed from the package P by sliding the enclosure 10, including the reinforcements 14, 15 and 16, downwardly to disengage the package at which time the enclosure 10 is inverted and repositioned about the package P in the manner shown in Figure 3 to enclose the package as shown in Figure 4. The side and end reinforcement members 14, 15 and 16 being of relatively stiff material will provide the enclosure 10 with sufficient stability so the same may be easily inserted over the open end of the package.

60 Accordingly, there has been provided a novel method of covering a package and a novel enclosure formed as part of the original protective wrapping for a package and which enclosure may be readily employed to protect the contents of an opened package from the elements, 65 and from being spilled.

70 Although the invention is illustrated as applied to a package of cigarettes to protect the same from spilling,

perspiration, rain, etc., it is understood that the invention may be applied to any type of package.

It is apparent that the invention is equally useful with packages wherein the tape 13 is positioned adjacent the bottom of the package or end wall 12, with the top of the package adjacent the end wall 12' being adapted to be opened to gain access to the contents of the package. In this instance the only difference in operation is that the enclosure 10 should be completely removed from the package before opening the top and need not be inverted before repositioning it about the opened package.

In the drawings and specification there has been set forth a preferred embodiment of the invention and although specific terms are employed, they are used in a generic and descriptive sense only, and not for purposes of limitation, the scope of the invention being defined in the claim.

I claim:

A covering for a package comprising a body portion formed of thin flexible material and having opposed side walls and a fixed end wall, a removable end wall, a tear tape connecting said removable end wall with said body portion, and a U-shaped reinforcing member formed of

5 relatively stiff material secured within said body portion with the web of the reinforcing member adjacent the fixed end wall of the body portion and the legs of the reinforcing member extending along two opposed sides of the body portion, the free ends of the legs on the U-shaped reinforcing member terminating adjacent the upper edge of the body portion whereby upon said tear tape being pulled to separate the removable end wall from the body portion to permit the package to be opened and the body portion removed, the U-shaped reinforcing member will 10 serve to slidably guide the body portion over the open end of the package to protect the contents of the same.
